UNITED STATES PATENT OFFICE.

REUBEN RAYMOND, OF NAPA, CALIFORNIA.

BASEBALL GLOVE.

1,421,308.

Specification of Letters Patent. Patented June 27, 1922.

Application filed July 27, 1921. Serial No. 487,849.

To all whom it may concern:

Be it known that I, REUBEN RAYMOND, citizen of the United States, residing at Napa, in the county of Napa and State of California, have invented certain new and useful Improvements in Baseball Gloves, of which the following is a specification.

This invention relates to a baseball glove, and particularly to the type known as a padded catcher's glove comprising two complete gloves, one within the other, and an intermediate padding at the front portion of the hand.

The invention has for an object to provide a novel and improved construction of glove by the insertion of a crotch piece between the fingers and secured to the longitudinal seams thereof; and also of the lacing by which the padding is removably retained between the inner and outer glove members.

Another object of the invention is to present an improved form of padding comprising palm, thumb and finger portions and provided with means by which it is held in position without direct attachment to the glove members.

Other and further objects and advantages of the invention will be hereinafter set forth and the novel features thereof defined by the appended claims.

In the drawings—

Figure 1 is a front elevation of the glove; Figure 2 is a rear elevation thereof;

Figure 3 is a rear elevation of the padding;

Figure 4 is a front elevation of the same;

Figure 5 is a detail plan of the crotch piece with the fingers separated;

Figure 6 is a section through the thumb members and the strap upon the padding;

Figure 7 is a detail perspective of the lacing terminal; and

Figure 8 is a detail of the crotch piece.

Like numerals refer to like parts in the several figures of the drawings.

The numeral 10 designates the outer glove member having the palm portion 11 provided with the integral finger fronts 12 and to which the thumb member 13 is secured. The back 14 of the outer glove member is formed of a series of strips which provide the finger backs 15 for the first, second and third fingers, while the back of the fourth finger is composed of a continuation 16 from the glove front. The finger

backs and fronts are secured together by longitudinal seams 17 and at the base or crotch of the fingers a crotch piece 18 is inserted and secured upon curved lines to 60 these seams. This piece is substantially triangular in shape with its base 19 toward the palm of the glove and its apex 38 curved and intersecting the rear seam 39 of the finger backs 15. The edges of the piece 18 65 are curved, as shown in Figures 5 and 8, to avoid abrupt or sharp angles at opposite sides of the finger crotch where secured to the finger seams. By providing curved seams at this crotch the glove is materially 70 strengthened against the intense impact strain of a fast thrown ball which is liable to break or injure the stitching at this point. A reinforcement is thus provided giving 75 comfort to the wearer and equalizing and balancing the strain in use, while also providing for the most economical manufacture as the finger pieces are reduced in size and are of regular shape.

The thumb and first finger may be connected by a web 20 as usual, and the glove back is cut away at 21 and provided with a securing strap and retaining means as at 22. The inner glove member 23 is substantially similar in construction and fits within 85 the outer member 10, but is not attached thereto except by a binding 24 about the cutaway portion 21 and a lacing 28 extending across the front of the glove at the wrist portion. This lacing comprises a 90 single strand starting at 25 beneath the thumb and cross laced in opposite directions to a point 26 beneath the fourth finger, where the free ends thereof are suitably knotted, as at 27, and inserted between the 95 inner and outer glove members, as indicated by dotted lines in Figure 1. This double lacing by a single piece materially increases the strength, while the slip knot is entirely concealed but adapted to be easily withdrawn and unlaced when it is desired to remove or replace the padding 30 which is inserted at the front between the inner and outer glove members.

This padding 30 comprises a front piece 105 31 patterned to form the palm, thumb and finger portions and a companion back piece 32 having the center of the palm portion thereof cut away, as at 33 to provide only a single thickness at this point, which in cooperation with the supplemental packing 34, 110 forms a pocket to receive and retain the

ball. The supplemental packing 34 comprises a stuffing between the layers of the padding and extends as usual across the wrist portion and longitudinally of the 5 thumb and fourth finger for a portion of the length thereof. The padding 30 is not fixedly attached to either glove member, but is held in position by an inwardly extending portion 35 beneath the first finger which is 10 formed upon a curve complementary to the inner edge of the thumb and provides a projection 37 upon said finger next the thumb, and the first finger is caused to spread or separate from the second finger. This prevents 15 the finger portions from working downward toward the palm as they are held by the reduced width of the padding at the crotch of the thumb. The padding is also provided at the back with a strap 36 extending from the thumb to the first finger and beneath which the thumb member of the inner glove is passed as the parts are assembled, as shown in Figure 6. This holds the padding against any lateral or cross wrinkling and securely retains it in proper position while permitting its ready and convenient withdrawal whenever necessary. The padding is preferably formed of a rough hairy fibrous material which offers a frictional resistance against the leather of the 25 glove to prevent displacement when in position.

The assemblage of the glove will be understood from the foregoing description and it will be noted that the use of the reinforcing crotch piece or quirk greatly strengthens and prolongs the life of the glove as it equalizes the strain upon the seams at this 30 point and provides greater comfort to the wearer under all conditions of use. Further this construction permits the most economical manufacture of the glove as the finger pieces are reduced in size and made regular in shape which provides for the cutting 45 of the leather with the least possible waste. The arrangement of the concealed knot of the lacing forms a more finished effect in the glove and prevents catching of the free ends and their accidental release. The double lacing adds strength at the wrist portion to resist the impact strain from contact with a ball, and the knot is adapted to be readily withdrawn when it is desired to unlace the glove for the removal of the padding or access thereto. The construction of the padding provides a single member for direct insertion between the glove members and obviates any fixed attachment thereto. The material and shape of the padding and strap 50 thereon securely retain it in position, yet permit its direct withdrawal and replacement in the most convenient manner.

The invention presents a simple, efficient and economically manufactured construction 65 of base ball glove and padding therefor

adapted to be formed in three complete members assembled in cooperative relation.

What I claim is—

1. A baseball glove comprising a front piece having finger members, a series of 70 back pieces having finger members, and a triangular crotch piece disposed at the crotch of the finger members with a curved apex at the back piece seams and its base at the front piece and secured to the 75 longitudinal seams of the fingers upon curved lines.

2. A baseball glove comprising a front piece having integral finger fronts, a series of back pieces having integral finger backs, 80 and a triangular crotch piece disposed between the fingers with its base toward the front and its curved edges secured to the longitudinal seams of the front finger members and having a curved apex intersecting the seams between the finger backs. 85

3. In a baseball glove, a complete outer glove member, a complete inner glove member, and a rough surfaced padding interposed between said members and having a 90 retaining projection upon the first finger opposite the thumb member thereof.

4. In a baseball glove, a complete outer glove member, a complete inner glove member, and a complete padding interposed between 95 said members and having an inwardly inclined face adjacent the thumb crotch, whereby the cross diameter thereof is reduced at that point.

5. In a baseball glove, a complete outer 100 glove member, a complete inner glove member having a thumb piece, and a complete removable padding member provided with a loop or strap beneath which the thumb of the inner glove member is adapted to 105 be passed as the glove is assembled.

6. In a baseball glove, interfitted glove members, and an interposed padding member comprising a complete front piece, a back piece having its central palm portion removed, and a supplemental packing between the pieces disposed to partially surround the removed portion. 110

7. In a baseball glove, interfitted glove members, and an interposed padding member comprising a complete front piece, a back piece having its palm portion partially removed, said padding member having an inwardly curved edge at the base of the forefinger next the thumb to provide a 115 portion of reduced width across the palm. 120

8. In a baseball glove, interfitted glove members each having thumbs, and a removable interposed padding member having a thumb and a strap extending from 125 the base of the thumb thereof to the base of the first finger, and adapted to receive the thumb member of the inner glove.

9. In a baseball glove, a complete outer glove member, a complete inner glove mem- 130

ber, a freely removable padding member having a reduced width in alignment with the thumb crotch, and a loop upon said padding member disposed to receive the thumb 5 of the inner glove member.

10. In a baseball glove, a padding member comprising thumb and finger portions and having an inwardly offset face at the base of the forefinger adjacent the thumb 10 crotch, said offset serving as an abutment to

retain the padding member in proper position within the glove.

11. In a baseball glove, a padding member comprising thumb and finger portions with a retaining projection at the base of 15 the first finger opposite the thumb, and a loop extending over said thumb portion at the base thereof.

In testimony whereof I affix my signature.
REUBEN RAYMOND.
